UNITED STATES PATENT OFFICE

GLENN W. CARPENTER, OF SCHENECTADY, NEW YORK, ASSIGNOR TO GENERAL ELECTRIC COMPANY, A CORPORATION OF NEW YORK

CIRCUITS FOR ELECTRON-DISCHARGE DEVICES

Application filed October 3, 1923. Serial No. 666,223.

My present invention relates to circuits adapted for use with electron discharge amplifiers and detectors, and more particularly to arrangements for eliminating disturbing effects in such circuits due to the use of periodically fluctuating voltage sources of supply.

The novel features which I believe to be characteristic of my invention are set forth with particularity in the appended claims, my invention itself, however, both as to its organization and method of operation will best be understood by reference to the following description taken in connection with the accompanying drawing in which Figs. 1 and 2 show diagrammatically two different circuit arrangements whereby my invention may be carried into effect.

In Fig. 1 I have indicated an electron discharge device 1 having a cathode 2 adapted to emit electrons, two anodes 3 and 4, and two grids 5 and 6. Grid 5 may be employed in the usual manner for controlling the current between cathode 2 and anode 4 by connecting the source of controlling voltage to conductors 7 and 8 in the usual manner for employing the device as an amplifier or as a detector. Anodes 3 and 4 are connected together and the plate or anode circuit of the device is supplied with current from a direct current generator 9. The use of a direct current generator as a source of plate supply gives rise to disagreeable noises in the telephone receivers 10 in the plate circuit due to commutation ripples, etc., if special means is not provided to eliminate the effect of the voltage fluctuations of the generator. It has been customary in the past to use large and somewhat expensive filter coils for this purpose.

I overcome the effect of the voltage fluctuations of the source 9 by connecting the grid 6 by means of a potentiometer connection to the resistance 11, which is connected adjacent the negative terminal of generator 9. The anodes 3 and 4 are connected by means of another potentiometer connection to a point in resistance 12, which is in series with resistance 11. The cathode 2 is connected to a point 13 between resistances 11 and 12. With this connection any point in resistance 11 will

be negative with respect to the junction point 13, and hence the grid 6 will always be negative with respect to the cathode 2.

The operation of the system described is as follows:—Assume that the circuit is out of adjustment and that disagreeable noises are heard in the telephone 10 due to the voltage fluctuations of the generator. The slider may then be moved along resistance 11 until a balance is obtained and silence occurs in the telephone. Silence will occur when the voltage fluctuations of the generator produce impulses on grid 6 just sufficient to create a pulsating current, superimposed on the normal current to plate 3, equal and opposite to the pulsating current to plates 3 and 4 produced by reason of their direct connection to the generator. It will be apparent from an analysis of the circuit described that the potential variations impressed upon grid 6 will be of the proper phase to compensate for the variations in plate current due to fluctuations in the voltage of the source 9. If the voltage of source 9 increases the current through resistance 11 will tend to increase and this will cause an increase in the negative potential applied to grid 6. This increased negative potential will in turn counteract the tendency toward an increase in plate current. On the other hand, a decrease in the voltage of source 9 will cause a decrease in the negative potential of grid 6, and permit the current flowing to plate 3 to increase thus counteracting the tendency for the current in the plate circuit to decrease.

In Fig. 2 I have indicated the application of my invention to a radio receiving system comprising three electron discharge devices 14, 15 and 16, having their plate circuits supplied with current from an alternating current source 17 through electron discharge rectifiers 18 and 19. Device 14 is connected to serve as a detector and devices 15 and 16 are provided with two grids 20 and 21. Grids 20 perform the usual function of controlling the current to the plates. The currents supplied to the plate circuits flow through resistance 22 and grids 21 are connected to a point in this resistance by means of the sliding connection 23. The operation

of the system shown in Fig. 2 is substantially the same as that of Fig. 1. The fluctuations in the rectified potential supplied to the plates are partly eliminated by the smoothing condenser 24 and the effect of the remaining fluctuations is counteracted by the potentials applied to grids 21.

While I have shown and described only two embodiments of my invention it will be apparent that many modifications in the apparatus and circuit connections employed may be made without departing from the scope of my invention as set forth in the appended claims.

15 What I claim as new and desire to secure by Letters Patent of the United States, is:—

1. The combination with an electron discharge device having an electron emitting cathode, an anode and a plurality of grids, of 20 a source of periodically fluctuating voltage connected in the anode circuit, and means for impressing upon a circuit connected between the cathode and one of the grids periodic voltage fluctuations of the proper phase and 25 value to neutralize the effect in the anode circuit of the device of the voltage fluctuations of the source connected therein.

2. The combination with an electron discharge device having an electron emitting 30 cathode, an anode and a plurality of grids of a source of periodically fluctuating voltage connected in the anode circuit and means for impressing upon the circuit connected between the cathode and one of the grids periodic voltage fluctuations derived from 35 said source of the proper phase and value to neutralize the effect in the anode circuit of the device of the voltage fluctuations of the source connected therein.

40 3. The combination with an electron discharge device having an electron emitting cathode, and anode and a plurality of grids, of a source of periodically fluctuating voltage connected in the anode circuit, a resistance 45 in the anode circuit and a connection from one of the grids to a point in said resistance for impressing upon that grid periodic voltage fluctuations of the proper phase and value to neutralize the effect in the anode circuit of 50 the voltage fluctuations of the source connected therein.

4. The combination with an electron discharge device having an electron emitting cathode, an anode and a plurality of grids 55 of a source of fluctuating voltage connected in the anode circuit, means for impressing upon a circuit connected between the cathode and one of the grids voltage fluctuations of the proper phase and value to neutralize the effect in the anode circuit of the device of 60 the voltage fluctuations of the source connected therein, and means for impressing signalling potentials upon another of said grids.

5. The combination in a system for the reception of signals of an electron discharge device having an electron emitting cathode, an anode and a plurality of grids and circuits connecting said cathode and said anode and 70 grids, one of said grid circuits having connections for receiving currents to be detected and another of said grid circuits having associated therewith means for supplying a suitable potential to eliminate undesired currents in the anode circuit.

6. The combination with an electron discharge device having an electron emitting cathode, an anode and a plurality of grids, of 80 a source of rectified alternating voltage connected in the anode circuit, and means for impressing upon a circuit connected between the cathode and one of the grids voltage fluctuations derived from said source and of the proper phase and value to neutralize the 85 effect in the anode circuit of the device of the voltage fluctuations of the source connected therein.

7. The combination with an electron discharge device having an electron emitting 90 cathode, an anode and a plurality of grids, of a source of rectified alternating voltage connected in the anode circuit, and means for impressing upon a circuit connected between the cathode and one of the grids voltage fluctuations derived from said source and of the proper phase and value to neutralize the effect in the anode circuit of the device of the voltage fluctuations of the source connected therein, and means for impressing signaling 100 potentials upon another of said grids.

8. The combination in a receiving system of a plurality of electron discharge devices connected in cascade, each of said devices having an electron emitting cathode, an anode and a plurality of grids, a source of periodically fluctuating voltage connected in the anode circuits of all of said devices, and means for impressing upon circuits connected between the cathode and one grid of each device periodic voltage fluctuations of the proper phase and value to neutralize the effect in the anode circuits of the devices of 110 the voltage fluctuations of the source.

9. The combination in a receiving system 115 of a plurality of electron discharge devices connected in cascade, each of said devices having an electron emitting cathode, an anode and a plurality of grids, a source of rectified alternating voltage connected in the anode circuits of all of said devices, and means for impressing upon circuits connected between the cathode and one grid of each device voltage fluctuations derived from said source of the proper phase and value to neutralize 125 the effect in the anode circuits of the devices of the voltage fluctuations of the source.

10. The combination with an electron discharge device having an electron emitting cathode, an anode and a grid of a source of 130

periodically fluctuating voltage connected in the anode circuit, and means for impressing upon a circuit connected between the cathode and the grid periodic voltage fluctuations of the proper phase and value to neutralize the effect in the anode circuit of the device of the voltage fluctuations of the source connected therein.

11. The combination with an electron discharge device having an electron emitting cathode, an anode and a grid of a source of periodically fluctuating voltage connected in the anode circuit, and means for impressing upon a circuit associated with said device periodic voltage fluctuations of the proper phase and value to neutralize the effect in the anode circuit of the device of the voltage fluctuations of the source connected therein.

12. The combination with an electron discharge device having an electron emitting cathode, an anode and a grid of a source of fluctuating voltage, a resistance connected between the cathode and anode and a second resistance connected between the cathode and grid, said resistances being connected in series with one another and in shunt to the fluctuating voltage source in such a way that the voltage drop across the second resistance serves to impress upon the grid a voltage which is always negative with respect to that of the cathode and which fluctuates in opposite phase with the voltage fluctuations impressed upon the anode.

13. The combination with an electron discharge device having an electron emitting cathode, an anode and a grid of a source of rectified alternating voltage connected to the anode circuit of said device, a resistance connected in series with said source and a connection to the grid from a point in said resistance which is always at a negative potential with respect to the cathode, said point being so chosen that the voltage fluctuations produced across said resistance and impressed upon the grid are of such value as to neutralize the effect in the anode circuit of the voltage fluctuations of said source.

14. In a system for supplying operating voltages to an electron discharge device having a cathode, an anode and a grid, a source of periodically fluctuating voltage, a resistance connected to said source and individual connections from each of the electrodes of said device to said resistance, said connections being so made that the potential impressed from said resistance upon the grid is always negative with respect to that of the cathode and fluctuates in opposite phase to the voltage fluctuations impressed upon the anode.

In witness whereof, I have hereunto set my hand this 1st day of October, 1923.

GLENN W. CARPENTER.

DISCLAIMER

1,792,275.—*Glenn W. Carpenter*, Schenectady, N. Y. CIRCUITS FOR ELECTRON-
DISCHARGE DEVICES. Patent dated February 10, 1931. Disclaimer filed
November 24, 1934, by the assignee, *General Electric Company*.

Hereby enters this disclaimer to that part of the claim in said specification
which is in the following words, to wit:

“14. In a system for supplying operating voltages to an electron discharge
device having a cathode, an anode and a grid, a source of periodically fluctuating
voltage, a resistance connected to said source and individual connections from each
of the electrodes of said device to said resistance, said connections being so made
that the potential impressed from said resistance upon the grid is always negative
with respect to that of the cathode and fluctuates in opposite phase to the voltage
fluctuations impressed upon the anode.”
